(57)

CLAIM

The ornamental design for a portable shelter with internal removable tent, as shown and described.

DESCRIPTION

FIG. 1 is a perspective view of a portable shelter with internal removable tent, showing the new design;

FIG. 2 is a front view thereof;

FIG. 3 is a rear view thereof;

FIG. 4 is a side view thereof; and,

FIG. 5 is a top view thereof.

The portion(s) shown in broken lines form no part of the claimed design.

1 Claim, 5 Drawing Sheets
